The ornamental design for a desktop electrophotographic printer, as shown and described.

DESCRIPTION

FIG. 1 is top, front, left side perspective view of a desktop electrophotographic printer showing our new design;

FIG. 2 is a front perspective view thereof;

FIG. 3 is a top, front, right side perspective view thereof;

FIG. 4 is a left side elevational view thereof;

FIG. 5 is a top plan view thereof, the bottom being plain and unornamented;

FIG. 6 is a right side elevational view thereof;

FIG. 7 is a top, rear, left side perspective view thereof;

FIG. 8 is a rear perspective view thereof;

FIG. 9 is a top, rear, right side perspective view thereof;

FIG. 10 is a top, rear, right side perspective view thereof showing the paper tray in extended position; and,

FIG. 11 is an enlarged view of the top, right control panel of the front cover.
